UNITED STATES PATENT OFFICE

2,440,885

TOY BOMBING DEVICE

William E. Zamboni, Owatonna, Minn.

Application December 18, 1944, Serial No. 568,570

8 Claims. (Cl. 273—95)

1

This invention relates to toys, and more particularly to a toy designed to simulate aerial bombing.

The toy disclosed herein comprises a target, and an instrument including a sighting device, a bomb rack, and release mechanism controlled by the operator for releasing toy bombs or darts from the rack when the sighting device is aligned on the target.

An object of the invention is to provide a toy of the type described wherein the operator may maintain the sighting device in vertical position while aligning it with the target.

A further object of the invention is to provide a toy of the type described wherein release of the projectiles will not interfere with the sighting of the instrument.

A further object of the invention is to provide a toy of the type described wherein the sighting device, bomb rack, and release mechanism are incorporated into a single unitary structure, and so designed that proper positioning of the sighting device will automatically position the bomb rack in correct relation to the target.

A further object of the invention is to provide a toy of the type described which shall be simple and economical to manufacture and sturdy and reliable in use.

Further objects and advantages of the invention will be apparent from the following description, taken in connection with the appended drawings, in which:

Fig. 1 is a plan view of a toy embodying the invention, certain parts being broken away to reveal the interior construction;

Fig. 2 is a vertical sectional view of the same, taken on the line 2—2 of Fig. 1;

Fig. 3 is a fragmentary sectional view taken on the line 3—3 of Fig. 2;

Fig. 4 is a vertical sectional view taken on the line 4—4 of Fig. 2;

Fig. 5 is a plan view of a modified form of the invention, with parts broken away to reveal the interior construction;

Fig. 6 is a view of the same in end elevation, as seen from the right of Fig. 5; and

Fig. 7 is a perspective view of the instrument and its target.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

The toy disclosed herein comprises a toy bombing instrument 10 and a target 12; the target may have mounted or marked thereon certain

2

designated objectives, as a factory building 13, a road intersection 14, and a cantonment 15. Where the toy is used in the playing of a competitive game, each of the players may be provided with one of the instruments 10, and the several objectives may be given weighted values, so that the hits made by the several players on the objectives may be tallied by using such weighted values.

10 In the form of the invention shown in Figs. 1 to 4, the instrument comprises a frame made up of parallel vertical side walls 17, 18, preferably formed of metal stampings, and deformed at their lower edges as indicated at 19 and 20 to form grooves which receive a fixed bottom piece 22 and a slide 24, located respectively at the rear and forward portions of the instrument. The upper edges of the walls 17 and 18 are joined by means of wall 26, which may be formed integral with one of the vertical walls and secured to the other, as by welding or soldering, and which is preferably inclined toward the rear of the instrument as shown, to facilitate grasping of the instrument by the operator.

25 At the forward end of the instrument, the walls 17, 18 are formed with flanges 27, 28 which engage a sighting cylinder 30. The upper end of the cylinder is provided with a fixed cover 32 secured thereto and provided with a central peep-hole 33. A retaining wire 34 extends diametrically of the peep-hole and has secured thereto the upper end of a thread or fine wire 36, the wire 34 being so bent as to retain the upper end of the thread 36 centrally of the peep-hole.

35 Cross-hairs 37, 38 are mounted at the lower end of the tube 30 in the usual relation, and may be secured in place in vertical slits at the lower end of the tube, which slits may be peened in the known manner to retain the cross-hairs in place. 40 The lower end of thread 36 is secured to the intersection 39 of the cross-hairs, which is preferably located forwardly of the axis of tube 30 by a slight distance, to compensate for the forward displacement of the tube relative to the bomb rack, hereinafter described. A sighting bead 40 is secured to the thread 36 toward the lower end thereof, sufficient slack being left in the thread to permit the bead a limited degree of swinging action away from its normal alignment with the intersection 39 of cross-hairs 37, 38. It will be seen that when the tube 30 is in vertical position, the peep-hole 33, bead 40, and intersection 39 will be in alignment.

45 The slide 24 is formed with a vertical flange 55 42, to which is secured the piston rod 44 of a piston 46. The piston 46 is mounted in a cylinder 47 fixed to the bottom piece 22 of the frame, the cylinder being closed at its inner end by means of an apertured plug 48. A compression spring 50 surrounds the piston rod 44 and tends to move the piston and slide to the position shown in Figs. 1 and 2.

The piston 46 is actuated by the operator by means of compressed air generated by a syringe bulb 52, of known construction, which is connected to the forward end of cylinder 47 by means of a flexible tube 54 and nipple 55 mounted in the side wall of the cylinder 47. It will be seen that compression of the bulb 52 will cause the piston 46 to move rearwardly, compressing spring 50 and correspondingly moving the slide 24, and that the force applied in actuating bulb 52 will not be transmitted to the body of the instrument to disturb the sighting thereof.

The bomb rack of the instrument is formed by a plurality of vertical tubes 56 mounted between the walls 17, 18 above the slide 24. Within the tubes are mounted a corresponding number of toy bombs or darts 58, preferably provided with tail fins 60 and having at their lower ends pins 62 designed to maintain the darts upright after being dropped, by embedding themselves in the material of the target 12.

The slide 24 is provided with a longitudinal slot 64 to receive the pins 62, and the darts 58 are provided with suitable shoulders adjacent the bases of the pins 62 to permit them to slide with a minimum of friction relative to the slide 24. The fins 60 are preferably of such shape and size, as shown, that they tend to retain the darts in alignment with their tubes 56 until they are released therefrom.

The various elements of the sighting tube, frame, and bomb rack thus far described are preferably formed of sheet metal stampings, and may be secured together in any convenient or conventional manner, as by soldering or welding, or, as in the case of the bottom member 22, merely by being clamped in position by the adjacent members.

In the operation of the device thus far described, the operator will seize the instrument in one hand and move the same over the target 12, at such height as may be prescribed by the rules, and with his eye at the peep-hole 33 will attempt to bring the bead 40 and intersection 39 of the cross-hairs into alignment with the target. When he has succeeded in doing this, the instrument will be in position for discharging the darts, since the bead 40 will indicate, by moving out of alignment with intersection 39, when the instrument is tilted from the vertical in the fore-and-aft direction, or canted in the lateral direction. When the sighting apparatus is thus correctly aligned with the selected objective, the operator will release the bombs by compressing the bulb 52, thereby moving slide 24 to the right, removing the support from the darts 58, and permitting them to fall by gravity upon the target. Upon release of the bulb 52, the spring 50 will restore the slide 24 to its original position, whereupon the tubes 56 may be reloaded.

In the form of the invention shown in Figs. 5 and 6, the construction is generally the same, and the elements are designated by the same reference numerals as in Figs. 1 to 4 except as hereinafter noted. In place of the release mechanism above described, there is shown a mechanical release comprising a lever 65 pivoted at 67 to an arm 68 secured to the wall 18. The inner end of arm 65 is pivotally secured in a slot 70 formed in a slide 72, so that when the handle 66 is moved forwardly, the slide 72 will be moved rearwardly, releasing the darts in the same manner as above described.

Although the invention has been described with particular reference to certain embodiments

thereof, it may be embodied in other forms and variously modified within the skill of artisans in this art; the invention is therefore not to be considered as limited except by the terms of the following claims.

I claim:

1. A toy bombing device comprising a magazine rack for projectiles, releasing means retaining the projectiles in the rack, and a sighting device comprising upper and lower sights and means interposed between said sights for indicating the position of the rack relative to the vertical.

15 2. A toy instrument for releasing gravity propelled projectiles comprising releasable means for retaining said projectiles, and a vertical sighting device comprising upper and lower sights, a flexible member connecting said sights, and a gravity actuated member secured to said flexible member for indicating the vertical relation between said sights.

20 3. The invention defined in claim 2, comprising in addition manually actuated means for releasing said releasable means connected to the retaining means by a flexible connection.

25 4. A toy device for simulating aerial bombing, comprising releasable means for retaining gravity-actuated projectiles, a sighting device comprising upper and lower sights, a flexible member connecting said sights, and a gravity controlled sighting member secured to said flexible member for indicating the vertical relation between said retaining means and the target.

30 5. A device of the class described, comprising an instrument freely movable into and out of vertical position and including releasable means for retaining projectiles, upper and lower sights associated with said releasable means, and a sighting member suspended between said sights and cooperating therewith to indicate the relation of said sights to the vertical and to the target.

35 6. The invention defined in claim 5, wherein said releasable means includes a horizontal slide and a pivoted lever operable to operate said slide.

40 7. The invention defined in claim 5, wherein said releasable means includes a horizontally movable slide operatively supporting said projectiles, and fluid pressure operated means for moving said slide to inoperative position.

45 8. A device for simulating aerial bombing comprising an instrument freely movable into and out of vertical position and including a slidable member for releasably retaining projectiles, and a sighting device associated with said slidable member and including upper and lower sights and a sighting member suspended therebetween and cooperating therewith to indicate the relation of said sights to the vertical and to the target.
